ROTARY VALVE

George Henry Kemp, St. Mellons, Cardiff, Wales,
assignor of one-half to John Blythe Campbell
Forrester, Cardiff, Wales

Application August 27, 1934, Serial No. 741,629
In Great Britain June 20, 1933

2 Claims. (Cl. 123—59)

This invention relates to rotary valves for use, among other purposes, to control the intake of explosive gases and the exhaust of burnt gases to and from the cylinders of internal combustion engines, and has generally in view to provide a valve which is continuously rotatable in a single direction, which is of simple, compact, sturdy construction and possesses long life, and which is highly efficient in operation.

10 The valve includes a body or casing having a bore, separate intake and exhaust ports providing communication between an engine cylinder and said bore, and exhaust ports leading from said bore. Within the bore is mounted a rotatable plug which itself has a bore and a port leading laterally therefrom through the side of the plug for alinement with the intake port at predetermined times to admit explosive gas or other operating fluid to the cylinder, while in the side of said plug is a recess for alinement with the exhaust ports at predetermined times to permit the escape of exhaust products from the cylinder. In this connection a special object of the invention is to provide the body or casing with dual exhaust ports leading from the plug accommodating bore and to provide the plug with a side recess which serves to provide communication between the exhaust port leading from the cylinder and first one of said dual exhaust ports, then both of said dual exhaust ports and, finally, the other of said dual exhaust ports, thereby to provide for an exceptionally free escape of exhaust products from the cylinder and, in a large measure, to eliminate the effects of back pressure in the cylinder.

35 With the foregoing and other objects in view, the invention consists in the novel features of construction, combination and arrangement of parts as will be hereinafter more fully described, illustrated in the accompanying drawing and defined in the appended claims.

In the drawing:—

Figure 1 is a central, longitudinal sectional view through a valve constructed in accordance with one practical embodiment of the invention; and

45 Figure 2 is a transverse section on the line 2—2 of Fig. 1.

Referring to the drawing in detail, 3 designates the valve body or casing having a longitudinally extending bore 3' in which is rotatably mounted the valve plug designated as 4, the plug being suitably journaled at its ends in the casing 3 and being equipped with a sprocket wheel 18 or other suitable means whereby it may be driven. Preferably the bore 3' and the plug 4 are tapered

and preferably, too, the plug is journaled at its ends in anti-friction bearings carried by the casing 3. Moreover, if the plug is tapered, spring means preferably are provided to urge the plug longitudinally thus to maintain the same tightly seated within the bore 3'. However, these are features which may or may not be incorporated in the valve as desired.

The body or casing 3 is intended to be bolted or otherwise secured in closing relationship to the end of an engine cylinder designated as 10 and as shown, for example, in Fig. 1, and through said body or casing are formed two ports 8 and 9 which are spaced apart longitudinally of the valve and which provide communication between the engine cylinder and the bore 3', the port 8 being provided for the escape of exhaust products from the cylinder and the port 9 being provided for the admission of explosive gases or other operating fluid to said cylinder.

20 Formed axially in the plug 4 and opening through one end thereof for connection with a source of operating fluid supply, such as a carburetor, is a bore 7 from which leads, through the side of the plug 4, a port 5 for alinement at predetermined times with the intake port 9 to provide communication between the bore 7 and the cylinder 10 for the admission of operating fluid to the cylinder.

25 Formed in the body or casing 3, one to either side of the exhaust port 8 and in the same plane, transversely of the valve, as said exhaust port 8, are two exhaust ports 11 and 12 which are alined with each other and which lead from the bore 3' through opposite sides of the casing 3. For alinement with these ports 8, 11 and 12 at predetermined times during rotation of the plug 4, said plug is provided with a port 6 in the form of a peripheral recess which is of a length, circumferentially of the plug, such that, as the plug is rotated in a single direction, communication is established first between the port 8 and one of said ports 11 or 12, then between the port 8 and both of said ports 11 and 12 and, finally, between the port 8 and the other of said ports 11 or 12, the direction of rotation of the plug being dependent only upon the relative angular disposition of the ports 5 and 6 and as will be readily apparent.

30 As a consequence of the dual ports 11 and 12, 50 one to either side of the port 8, and the port 6 serving to establish communication between said ports 8, 11 and 12 as set forth, an exceptionally free exhaust from the cylinder 10 is provided and back pressure effects on the working of the en- 55

gine piston within the cylinder are in a large measure eliminated since, by the time the exhaust products tend to build up any appreciable back pressure in the port 11 or 12 with which the port 8 first is placed in communication, the path of the exhaust is shifted to the other port 11 or 12 which is free of back pressure creating gases or fluid.

The body or casing 3 preferably is of hollow construction to provide spaces 13 to receive cooling water, and, as shown, ports 14 and 15 are provided in the casing 3 for the circulation of cooling water through said spaces 13. Moreover, the body or casing 3 preferably is provided with ducts 16 leading to the plug 4 so that a lubricant may be supplied to said plug.

As illustrated in the present instance, the plug 4 is journaled at its ends in ball bearings 17 and the casing 3 is provided with threaded openings 20 to receive bolts for fastening a carburetor or the like to said casing in fuel supplying relationship to the port 7 in the plug 4.

Without further description it is thought that the construction, operation and advantages of the invention will be readily understood. It is desired to point out, however, that the construction illustrated is readily capable of modification in various respects within the spirit and scope of the invention as defined in the appended claims.

I claim:—

1. A rotary valve comprising a casing having a bore and provided at longitudinally spaced points with intake and exhaust ports opening into said bore to provide communication between a

cylinder and said bore, said casing further having a pair of exhaust ports leading from said bore one to either side of said first mentioned exhaust port, and a plug rotatable within said bore and provided with an axial intake passageway and with a port leading laterally from said passageway through the side of the plug for alignment at predetermined times with the intake port in the casing, said plug further being provided with a peripheral recess to aline at predetermined times with the exhaust ports, said recess being of a length such that during rotation of the plug it provides communication first between the first mentioned exhaust port and one of the pair of exhaust ports, then between the first mentioned exhaust port and both of the pair of exhaust ports, and then between the first mentioned exhaust port and the other of the pair of exhaust ports.

2. A rotary valve comprising a casing having a bore and provided with an exhaust port opening into said bore to provide communication between a cylinder and said bore, said casing further having a pair of exhaust ports leading from said bore one to either side of said first mentioned exhaust port, and a plug rotatable within said bore and provided with a peripheral recess to aline at predetermined times during rotation of the plug with said first mentioned exhaust port and during its alinement with said port to aline first with one and then with the other of said pair of exhaust ports.

GEORGE HENRY KEMP.
